UNITED STATES PATENT OFFICE

2,128,138

DOOR STRUCTURE

Louis J. Goran, Brooklyn, N. Y., assignor to
 Truscon Steel Company, Youngstown, Ohio, a
 corporation of Michigan

Application October 23, 1933, Serial No. 694,896

4 Claims. (Cl. 20—19)

As is generally known, piers, and particularly those for large ocean-going steamships, are equipped with large doors along their sides, the arrangement being such that as many may be opened as desired for the loading and unloading of the cargo, and likewise for passengers. Practically all the piers of larger size are of double deck or two-story construction, the passengers ordinarily passing between the ship and piers on the upper floor. It is also a fact that upon the departure or arrival of a steamer there is a large assembly of friends and relatives so that means must be provided to keep such persons within certain safety zones.

15 Heretofore it has been the practice to have wooden guards or fences that are placed across the door openings after the doors have been opened. These fences are removable and therefore require storage-space, which is an important item on piers.

The object of the present invention is to provide a door structure which in its specific character is peculiarly adapted for piers, and in which a guard is provided that is in effect a part 25 of the door structure, thus making it possible to open the door and yet leave a guard that will prevent persons passing beyond a certain zone and being in danger of falling through or from the open doorway.

30 An embodiment of the invention, which at present is considered the preferable one, is illustrated in the accompanying drawings, wherein Figure 1 is an inside elevation of the door structure in its operative or entirely closed position.

Figure 2 is a vertical sectional view therethrough substantially on the line 2—2 of Figure 1.

Figure 3 is a detail sectional view on the line 40 3—3 of Figure 1.

Figure 4 is a view in inside elevation of the upper section of the upper leaf.

Figure 5 is a similar view of the lower section of the lower leaf.

45 Figure 6 is a horizontal sectional view on the line 6—6 of Figure 1.

Figure 7 is a detail sectional view on the line 7—7 of Figure 6.

Figure 8 is a horizontal sectional view on the 50 line 8—8 of Figure 2.

Figure 9 is a detail vertical sectional view on the line 9—9 of Figure 1.

Figure 9a is a detail perspective view of one of the holding lugs.

55 Figures 10 to 14 inclusive are vertical sectional

views diagrammatic in their nature, showing the different relations the door elements may be caused to assume.

The door structure and its operating means in its general make-up, and save for the modifications 5 hereinafter explained in detail, correspond to the disclosure in Letters Patent of the United States granted to David H. Morgan, No. 1,789,189, January 13, 1931, and therefore reference may be had to that patent for a more specific disclosure, 10 particularly of the operating mechanism.

Using the same reference letters as appear in that patent to designate generally corresponding parts, the lower leaf of the door is shown at A, and is adapted to register with the upper door leaf B by a sliding movement accomplished through the movement of the leaf A upwardly behind the leaf B and guided by the members C carried at opposite sides of the leaf B. The upper leaf B has a hinge mounting at D at the 15 top or lintel portion of the doorway, so that when the two door leaves are telescoped, they are free to swing together inwardly and upwardly to a fully open position.

Considering now generally the operating mechanism, the same includes a pair of lifting levers G, to the central portions of which the lower leaf is centrally pivoted as shown at H. The lifting levers are provided at their ends with rollers 3 that are adapted to travel in trackways 5 30 whose upper portions curve rearwardly from a vertical to a horizontal relation. The lifting levers G are elevated by cable chains 7 operating over sprocket wheels 8 carried by an overhead cross shaft 9. Suitable mechanism, including a 35 depending hand chain 16a, is provided for turning the rock shaft, all of which may be as explained in the above-entitled Morgan Patent No. 1,789,189.

In the present construction the lower leaf A 40 of the door is divided horizontally into separable sections 15 and 16 located edge to edge and movable either together or separately.

As perhaps best seen in Figure 5 the lower section 15 includes a frame having an upper 45 horizontal bar 17, a lower bar 18, an intermediate bar 19, and end bars 20. Connecting the lower bar 18 and intermediate bar 19, may be vertical bars 21, and the spaces between these bars 18, 19 and 21 may be closed by suitable panel 50 sheets 22. The space between the upper bar 17 and intermediate bar 19 is preferable open. It is to the central portion of the lower section, in line with the intermediate bar 19, that the lifting bars G are pivotally connected at H. As 55

will be noted by reference to Figure 6, for example, the end bars 20 may be of channel formation, and secured to them, in the channel, are angle bars 23 having inset flanges 24 forming guides.

Referring particularly to Figure 4, where the upper section 16 of the leaf A is illustrated, this section consists of an upper horizontal bar 25, a lower horizontal bar 26, end bars 27 and intermediate vertical bars 28. The spaces within these various bars may be closed by suitable panel plates 29. It will be noted that the end bars 27 project below the lower bar 26, as shown at 30, and by reference to Figure 6, for example, this bar 30 includes angle plates 31 having outstanding flanges 32 spaced apart and slidably embracing the guide flanges 24 of the lower section 15. It will thus be evident that the upper section 16 can be moved upwardly and downwardly on the lower section, and when moved downwardly, the paneled portion 29 will occupy the otherwise open space between the bars 17 and 19 of the lower section, thus completely closing said lower section, or in other words, making an entirely closed leaf A.

In order that the upper section 16 may be moved easily with respect to the lower section 15, it is suspended by cables 33, shown particularly in Figure 1, said cables passing over suitable pulleys 34 and having depending from their outer or free ends counterweights 35, which as shown in Figure 3, are located in the same boxings as the counterweights W for the door structure as an entity (see Morgan No. 1,789,189). Furthermore the lower frame bar 26 of the upper section 16 may be provided with suitable handles 36 for manipulating the section.

It will thus be seen that the upper section 16 may be individually raised and lowered with respect to the lower section 15 of the lower leaf A, and if the leaf A is at its lowered position when the upper section is elevated, the lower section will constitute a guard across the doorway. With that purpose in view and as shown in Figures 2 and 9, the top bar 19 of the lower section 15 may be in the form of a channel bar, and in the channel thereof, is secured by screws 37 or other suitable devices, a hand rail 38 that projects above the bar 19. The lower bar 26 of the upper section 16 may be a channel bar also, and when the upper section is lowered, it will enclose this hand rail.

It is of course desirable that the lower door leaf A should also be movable as an entity, and therefore means are provided for detachably securing together the sections 15 and 16. To this end there is journaled in the lower portion of the frame bars 21, a horizontal rock shaft 39 and secured to the ends thereof are collars 40 carrying latch hooks 41. The depending extensions 30 of the upper section have at their lower ends inwardly extending keeper lugs 42 that are adapted to be overhung by the latch hooks 41 when the two sections are together. The rock shaft is provided with suitable operating means. This may take the form of a hand lever 43 secured thereto, and if desired, a foot treadle 44. A coiled spring 45, connected to the shaft and surrounding the same, serves to bring the latch hooks 41 to their operative positions when the shaft is released, and the shape of the latch hooks is such, as will be clear by reference to Figure 7, that when the upper section is moved downwardly, the lugs 42 will pass the hooks, forcing the same to one side until the hooks will engage over said lugs.

With this structure it will be evident that the door members may be made to assume various relations. Thus, as shown in Figure 10, the two leaves A and B may be so extended as to completely close the doorway. If the sections 15 and 16 are latched together, in their closely related positions, the door structure may be operated in the usual manner, or as disclosed in the Morgan Patent No. 1,789,189. That is to say the two sections 15 and 16 will first be moved vertically to a position behind the leaf B, as illustrated in Figure 11, by the elevation of the lifting levers G, after which the upper ends of the levers moving rearwardly, will cause the leaves A and B to swing upwardly and rearwardly, as indicated in Figure 12, to a fully open position, as shown in Figure 13. Whenever it is desired to use the lower section 15 of the leaf A as a guard, the door may be closed to the position shown in Figure 10, after which the section 16 is unlatched from the section 15 and raised to a position behind the leaf B, leaving the lower section 15 across the door opening, where it serves as a guard, as shown in Figure 14.

With this construction therefore it will be evident that a section of the door itself is utilizable as a guard, thus adding nothing to the space occupied and eliminating the necessity of fences or removable guards that must be put in place and taken away and stored. The structure moreover is simple and the guard is an exceptionally effective one in that there is no danger of its displacement by lateral pressure when it is in place and in action.

From the foregoing, it is thought that the construction, operation and many advantages of the herein described invention will be apparent to those skilled in the art without further description, and it will be understood that various changes in the size, shape, proportion and minor details of construction may be resorted to without departing from the spirit or sacrificing any of the advantages of the invention.

What I claim, is:

1. In a combined door and guard, the combination with a doorway, of a door for the doorway, said door comprising a pivotally mounted upper leaf and a lower leaf that slides on the upper leaf to and from a position below the same, said lower leaf comprising relatively slidably sections, means for elevating the lower leaf and swinging it and the upper leaf to open position, said means including sliding and swinging lifting levers pivoted to the lower section of the lower leaf, the upper section of the lower leaf having a depending extension provided with an inwardly offset portion and slidably mounted on the lower section, a latch carried by the lower section for engaging the said laterally offset portion to secure the sections together, and counterbalancing means connected to the upper section for assisting in raising the same from the lower section when the two sections are unlatched and the lower section remains depressed.

2. A combined door and guard for doorways including an upper leaf and a lower leaf, said lower leaf being divided into an upper section and a guard section, guide tracks at opposite sides of the doorway, lifting levers movable in said tracks, means for pivotally mounting said guard section on said lifting levers, latch means carried by the lower portion of the guard section, said guard section including a frame-work having end bars projecting above the point where the guard section is pivoted to the lifting levers, guide means carried at the inner sides of said end bars, side 75

bars carried by the upper section and extending below the bottom edge thereof, guide means carried by the outer faces of said end bars of the upper section for mating with the guide means on the inner faces of the end bars of the lower section, and inwardly offset keeper elements carried by the lower portions of the end bars of the upper section and adapted to be engaged by the said latch means at the bottom of the guard section to releasably connect said upper end guard sections together to constitute the lower leaf, and counterbalance means connected to the upper section of the lower leaf.

3. A door leaf for doorways comprising an upper section and a lower guard section, said guard section including upwardly extending end bars and said upper section including downwardly extending end bars, cooperating guide elements respectively on the end bars of the guard section and upper section to interconnect said sections for sliding movement, keeper means on the lower ends of the end bars of the upper section, and latch means carried by the bottom portion of the guard section, said latch means including a spring tensioned rock shaft having latch hooks at opposite ends thereof for engaging with said keeper means of the upper section, a lever carried by said rock shaft for controlling its movement to bring the latch hooks into and out of engagement with the keeper means on the end bars of

the upper section, means for moving both sections of the leaf when they are latched together, and counterbalance means for moving the upper section independently of the guard section.

4. In a combined door and guard, the combination with a doorway, of a door for the doorway, said door comprising a pivotally mounted upper leaf and a lower leaf that slides on the upper leaf to and from a position below the same, said lower leaf comprising relatively slidable top and bottom sections, sliding and swinging lifting levers pivoted to the bottom section of the lower leaf for elevating and swinging the entire lower leaf and the upper leaf into open position, the bottom section of the lower leaf having upright members at opposite ends thereof and the top section of the lower leaf having downwardly directed extensions at opposite sides thereof for slidably interengaging with the upright members of the bottom section, a latching device carried by the bottom section for engaging with the downwardly directed extensions on the top section to releasably connect said top and bottom sections together, and counter-balancing means connected to the top section and assisting in raising the same from the bottom section when the two sections are unlatched and the bottom section remains in its lowered position.

LOUIS J. GORAR. 30
